UNITED STATES PATENT OFFICE.

MORRIS I. KATZ, OF SPRINGFIELD, MASSACHUSETTS.

DESIGN FOR A BOTTLE.

Application filed May 4, 1922. Serial No. 2,077. Term of patent 14 years.

To all whom it may concern:

Be it known that I, MORRIS I. KATZ, a citizen of the United States of America, residing at Springfield, in the county of Hampden and Commonwealth of Massachusetts, have invented a new, original, and ornamental Design for Bottle, of which the following is a specification, reference being had to the accompanying drawing, forming a part thereof.

The figure is an elevational view of a bottle showing my new design.

I claim:

The ornamental design for a bottle as shown.

MORRIS I. KATZ.
